United States Patent Office

Des. 209,022
Patented Oct. 24, 1967

209,022

EXPOSURE METER

John Gugliotta, Clark, and Kenneth J. Riddle, Nutley,
N.J., assignors to Weston Instruments, Inc., Newark,
N.J., a corporation of Delaware

Filed Mar. 7, 1966, Ser. No. 1,310

Term of patent 14 years

(Cl. D61—1)

FIG.1

FIG.2

FIG.3

FIG. 4

FIG. 5

FIG. 6

FIG. 1 is a front view of an exposure meter showing our new design;

FIG. 2 is another front view of the exposure meter showing an alternate position for the scale;

FIG. 3 is a back view of the exposure meter;

FIG. 4 is a left side view of the exposure meter;

FIG. 5 is a right side view of the exposure meter; and

FIG. 6 is a top view of the exposure meter.

The essential features of the design reside in the full line portions of the drawings.

We claim:

The ornamental design for an exposure meter, substantially as shown and described.
